UNITED STATES PATENT OFFICE.

NEHEMIAH T. FOLSOM, OF BOSTON, MASSACHUSETTS.

DUST-PAN.

SPECIFICATION forming part of Letters Patent No. 329,382, dated October 27, 1885.

Application filed September 29, 1884. Serial No. 144,254. (No model.)

To all whom it may concern:

Be it known that I, NEHEMIAH T. FOLSOM, of Boston, in the county of Suffolk and State of Massachusetts, have invented certain Improvements in Dust-Pans, of which the following is a specification.

This invention has for its object to improve the construction of the forward edges of dust-pans, so that said edges will be practically inflexible and not liable to be indented or distorted by the usage to which dust-pans are ordinarily subjected.

The invention consists in a dust-pan having its forward edge stiffened by a metal strip or strips applied to the body of the pan, the sheet metal forming the body of the pan being turned up a little near the front edge, and then inclined forward and downward, forming a protuberance, and the space beneath the same being filled with a rigid piece, which extends forward of the body portion and is reduced to a thin edge at front.

In the drawing the figure is a longitudinal sectional view of the body of a dust-pan with my improved strengthening-piece applied.

a indicates the body or main portion of the pan, which has a ridge or protuberance formed near the front edge thereof by the turning up of the thin sheet metal of which the pan-body is composed.

b indicates the forward edge of the strengthening-piece, *s*, which is nearly triangular in cross-section and comes to a thin edge at the front. This piece *s* is preferably of steel, and is firmly secured to the under surface of the pan-body *a*, and the front edge, extending forward of that of the pan-body, forms the wearing-edge of the dust-pan. The thick part of the re-enforce piece *s* fills the space under the protuberance *c* of the pan-body. The protuberance *c* is thus held against collapse when weight falls upon the front portion of the pan.

What I claim is—

A dust-pan having its main body portion composed of the usual thin material and having a protuberance or rib near the front edge thereof, extending across the pan, and a rigid piece filling the space beneath said protuberance, extending forward of the body of the pan proper to a thin edge, substantially as set forth.

In testimony whereof I have signed my name to this specification, in the presence of two subscribing witnesses, this 19th day of September, 1884.

NEHEMIAH T. FOLSOM.
